United States Patent Office

Des. 190,766
Patented June 27, 1961

190,766

TRANSPORTABLE TELEVISION UNIT

Sesto I. Chiarello, Los Angeles, Calif., assignor to Packard Bell Electronics Corporation, a corporation of California

Filed Oct. 5, 1959, Ser. No. 57,784

Term of patent 14 years

(Cl. D56—4)

FIGURE 1 is a front perspective view of a transportable television unit, embodying my new design;

FIGURE 2 is an end elevational view; and

FIGURE 3 is a rear elevational view.

The dominant features of my design reside in the portion shown in full lines.

I claim:

The ornamental design for a transportable television unit, substantially as shown and described.
